UNITED STATES PATENT OFFICE.

ALLEN J. RISHEL, OF READING, PENNSYLVANIA.

ELECTRIC HANDLAMP.

Application filed January 23, 1923. Serial No. 614,376.

To all whom it may concern:

Be it known that I, ALLEN J. RISHEL, a citizen of the United States, residing at Reading, in the county of Berks and State 5 of Pennsylvania, have invented certain new and useful Improvements in Electric Hand-lamps, of which the following is a specification.

This invention relates to improvements in 10 electric hand lamps, and the object in the present instance is to provide a device that may be easily and conveniently secured to and carried on the hand, so that, when provided with a suitable source of electrical 15 energy, as for instance a pocket battery, the movement of the hand, to which the lamp is attached will carry the light wherever it is wanted.

The device is particularly adapted for use 20 while working in dark places, as for instance the interior of a vehicle or like place in which it is difficult to secure light at all angles.

Another purpose in its use is for the 25 pedestrian to carry it while walking at night, particularly on roads travelled by vehicles.

The invention is more fully described in 30 the following specification and clearly illustrated in the accompanying drawing, in which:—

Figure 1 is a side elevational view of the device, and

Figure 2 is a plan view thereof.

The numeral 1 designates a casing or shell, 35 which is provided with any simple electrical switch 2 and with the usual posts for electrical connections 3. This casing is provided with a base plate 4 whose extremities 40 are bent or curved downwardly, as at 5 and the ends thereof are slotted to receive a suitable fastening means, preferably in the form of a strap of elastic material, 6, adapted to engage the hand, with the base plate resting 45 on the back of the hand.

The numeral 7 designates an electric bulb, 50 secured in a suitable socket in the casing 1, and 9 is a guard attached to the casing and adapted to protect the bulb from break-

As is evident, the strap is placed about the hand, with the lamp on the upper or outside of the hand, and the battery, to which the electric connections 3 are made, is preferably carried in the user's pocket. 55

The switch, by means of which the current is controlled, may be so located that its actuation may conveniently be accomplished by the thumb of the hand on which the lamp is secured, thus permitting the uninterrupted 60 use of the other hand at all times.

The casing 1 is preferably formed with a concave surface immediately below and surrounding the bulb, to produce a reflector 65 for the light rays.

The device, or any portion thereof, may be made of metal of light weight, suitably plated or polished, and the securing strap may be of any suitable material, such as woven elastic, or leather provided with a 70 buckle or any other means of securing it to the hand.

The device may be varied in form and details of construction to suit circumstances, 75 without departing from the spirit of my invention, and I do not therefore desire to limit myself to the exact form of device illustrated.

Having thus described my invention, I claim and desire to secure by Letters Patent:—

In a hand electric lamp, the combination of a hollow cylindrical casing provided with a depression in its top to form a reflector, a threaded opening in the top centrally of 85 said depression to form a lamp socket, a lamp in the socket, a lamp guard engaging said top, a source of current, a circuit including said source of current and said lamp, a switch in said circuit housed within the casing, means for actuating said switch projecting through the wall of the casing and means mounting said casing upon the hand in such position as to permit ready actuation of the switch by the thumb of the 90 hand. 95

In testimony whereof I affix my signature.

ALLEN J. RISHEL.
